DROP HAMMER

Frank J. Vlcek, Cleveland, Ohio, assignor to The
Vlcek Tool Company, Cleveland, Ohio, a cor-
poration of Ohio

Application December 22, 1930, Serial No. 503,970

15 Claims. (Cl. 78—29)

This invention relates to drop hammers and has for an object the provision of a new and improved construction of this type.

In the drawings accompanying this specification and forming a part of this application I have shown, for purposes of illustration, one form which my invention may assume, and in these drawings:

Figure 1 is a front elevational view of an embodiment of the invention.

Figure 2 is a side elevational view of said embodiment.

Figure 3 is a fragmentary view similar to Figure 2 showing the hammer raising mechanism in released position.

Figure 4 is an enlarged fragmentary vertical sectional view of the mechanism, showing the operating rolls in engaged position and the supporting dogs in disengaged position.

Figure 5 is a view similar to Figure 4 showing the rolls disengaged, and the dogs engaged, with reference to the tail piece means of the hammer head.

Figure 6 is an enlarged horizontal sectional view corresponding to the line 6—6 of Figure 1.

Figure 7 is an enlarged fragmentary horizontal sectional view corresponding to the line 7—7 of Figure 1.

Figure 8 is an enlarged horizontal sectional view of the mechanism showing the locking dogs and the operating mechanism therefor.

Figure 9 is an enlarged horizontal sectional view corresponding to the line 9—9 of Figure 8.

Figure 10 is a vertical sectional view corresponding to the line 10—10 of Figure 8, showing parts of the mechanism in elevation.

Figure 11 is a detailed horizontal sectional view corresponding to the line 11—11 of Figure 1.

Figure 12 is an enlarged fragmentary vertical sectional view of the clutch mechanism employed in said embodiment, showing parts of the cooperating construction in elevation, while

Figure 13 is an enlarged top plan view of the construction disclosed in Figure 12, portions thereof being shown in horizontal section.

The embodiment of my invention herein shown comprises a base support 12 which may be sunk a suitable distance into a floor to provide a firm anchorage therefor. The base 12 is provided with a platform 13 for the accommodation of a die support 14 detachably fixed in position by set screws 15 carried by set screw supports 16 affixed to the platform 13, and the die support 14 may have any suitable means by which a die may be secured thereto.

Secured to the upper portion of the base support 12 and reaching upwardly therefrom to a connecting head 17 are spaced standards 18 and 19, provided along their inner surfaces with projecting ribs 20 receivable in similarly formed

guide grooves in the hammer head 21, the latter being adapted to be reciprocated vertically between the said standards 18 and 19 as will be understood, and carrying a suitable die 22 adapted for cooperation with a die which may be attached to the die support 14. The upper end of the hammer head 21 has secured thereto tail piece means 23 which may comprise a pair of spaced boards 24—24, each substantially rectangular or diamond-shaped in cross-section providing V-shaped contours with the corners truncated as indicated at 25, the boards 24—24 extending upwardly through suitable openings in the head 17 and into engagement with hammer actuating means.

The hammer actuating means comprises a pair of rolls 26 and 27, each provided with a pair of V-shaped grooves 28 which accommodate the V-shaped contours of the boards 24—24. The roll 26 is keyed to a shaft 29, the opposite ends of which are supported in eccentric bearings 30 and 31, rotatably journaled in upstanding side plates 32 formed upon the head plate 19, and the shaft 29 is driven by a suitable pulley 33 actuated by a belt 34, taking over a pulley 110, fixed to the shaft 85 111 driven by a motor 112 supported upon a platform 113, carried by the side plates 32. The eccentric bearing members 30 and 31 are reduced at their inner ends as indicated at 35 for accommodation of segmental housing members 36 having flanges 37 secured by locking bolts 38, the housing members being movable with the eccentric bearings 30 and 31. The roll 27 is constructed and mounted in the same manner as the roll 26 and similar reference characters are employed to designate like parts of the two mountings; and the shaft 29 of the roll 27 is driven by a separate motor 114 through a belt 115, and the two rolls 26 and 27 are therefore rotated in unison though in opposite directions.

Each of the eccentric bearing members 30 and 31 projects outwardly beyond the adjacent supporting plate 32, and each has a collar 39 rigidly affixed thereto and provided with a crank 40 pivotally secured to one of the links 42, and the opposite ends of said links 42 are pivotally connected to a reciprocating block 43, the latter being mounted for vertical reciprocation in the guides 44 provided upon the adjacent supporting plate 32. The connection of the links 42 to the block 43 is by means of bolts 45, and such bolts may be employed to secure the links 42 to the upper portion of the block 43, or placed in the holes 46 at the lower portion of the block, thus to vary the oscillating movement imparted to the cranks 40—40 by the links 42—42. This mechanism provides interconnected lever means which act in a manner similar to toggle levers to oscillate the bearings 30 and 31 of the rolls 26 and 27 and effect simultaneous approach or recession of the 115 120

rolls 26 and 27 with reference to the tail boards 24—24.

Mechanism is provided for effecting reciprocation of the block 43 in timed relation, such 5 mechanism comprising an oscillatable bar 47 supported adjacent its opposite ends by bearings 48—48, and secured to the upper end of the rod 47 is a cam 49 on the face of which rides a roller 50 carried by the lower end of a post 51 secured 10 to the block 43, whereby oscillation of the cam 49 effects reciprocation of the block 43. At the lower end of the rod 47, and at one side thereof, is secured a laterally extending lever 52, and at the opposite side of the rod 47 is secured a laterally extending lever 53 of greater length than the lever 52. Cooperable with the lever 52 is a 15 slidable trip member 54 having at one end a roller 55 engageable with the inner surface of the lever 52 and having at its opposite end a roller 56 engageable with a cam 57 formed at the lower portion and on the rear side of the hammer head 21, the trip member 54 being slidably carried by a bracket 570 located adjacent the lower end of the oscillatable rod 47 and secured to the adjacent flange 58 of the standard 19 by means of a bolt 59. A second trip member 60 is provided at the opposite side of the oscillatable rod 47, slidably supported in a bracket 61, having a roller 62 at its inner end for engagement with a cam 63 20 on the upper forward portion of the hammer head 21 and having a roller 64 at its opposite end adapted for engagement with the inner surface of the lever 53. Accidental oscillation of the rod 47 is prevented by a latch member 71 cooperating 25 with a collar 72 mounted at the lower end of the rod 47, provided in its periphery with a pair of notches 73 adapted for the accommodation of a tooth 74 on the latch 71. The latch 71 is pivoted at one end to a post 75 on the adjacent standard 19 and at its opposite end is resiliently pressed 30 toward the collar 72 by a spring 76. When the rod 47 is oscillated to the limit of its movement in one direction, the tooth 74 will engage one of the notches 73, and when the rod 47 is positively 35 moved to the limit of its movement in the opposite direction, the tooth 74 will engage the other notch 73, thereby preventing accidental movement of the rod 47.

The bracket 61 is mounted for vertical sliding 40 movement along the side portion 58 of the standard 19 through the provision of interengaging guide means 65, and vertical reciprocation of said bracket 61 is preferably effected through threaded engagement with a screw 66 confined to 45 rotation and mounted in suitable bearings 67.

The screw 66 may be rotated in one direction or the other to raise or lower the bracket 61 and trip member 60, and thereby regulate the length of stroke of the hammer head 21, and mechanism 50 for bringing about this operation comprises an extension 68 upon the screw 66, having a bevel gear 69 secured thereto and meshing with bevel gears 116 and 117 rotatably mounted upon the motor drive shaft 118, the gear 116 having a 55 conical recess in its inner face providing a conical clutch surface 119 and the gear 117 having a similar recess providing a clutch surface 120, and disposed between the gears 119 and 120, and splined to the shaft 118 is a tapered clutch member 121 having a tapered clutch surface engageable with the clutch surface 119 of the gear 116, and a tapered clutch surface engageable with the clutch surface 120 of the gear 117, it being apparent that one or the other of the gears 116 75 and 117 may drive the bevel gear 69 and rotate

the screw 66 in one direction or the other, depending upon whether it is desired to elevate or lower the bracket 61. The clutch member 121 has a collar 122 affixed thereto and provided with projecting pins 123 adapted for the reception of slotted portions 124 of a shifting fork 125, pivotally supported as at 126, and said fork is adapted to be oscillated by a rocking lever 127 to which the fork 125 is connected, and secured to one end of the rocking lever 127 is a tension spring 128 connected to the platform 113 of the machine; the opposite end of the rocking lever 127 has one end of an operating rod 129 connected thereto, and the rod extends downwardly and is connected to the outer end of a lever 130 pivotally connected by a link 131 to a relatively small foot pedal 132, pivoted at 133 to the base 12. Secured to the rod 129 are limit stops 134 and 135 adapted to be engaged by the bracket 61 at the limit of its downward or upward movement, operating to shift the rod 129 in the direction in which the bracket 61 is moving and thereby cause the shifting fork 125 to automatically shift the clutch member 121 into neutral position at the upper and lower limits of movement of the bracket 61.

Means are also provided for automatically engaging the tail board means 23 of the hammer to arrest the hammer head 21 in elevated position, such means comprising a pair of opposed dogs 77 and 78, each of which is provided with a pair of V-shaped grooves 79 adapted for accommodation of the V-contours of the tail boards 24. The dog 77 is pivotally mounted upon a cylindrical sleeve 80 having a lateral extension 81 projecting through a slot 82 in the rear portion of the dog 77, and the outer end of the extension is pivotally connected to an angular portion 83 of a rod 84, the lower end of which is fixedly though adjustably secured to a bracket 85 by lock nuts 86. The sleeve 80 in turn is eccentrically mounted upon a cylindrical member 87 having trunnions 88 eccentric thereto and rotatably mounted in bearings 89 carried by upstanding side walls 90 upon the head plate 17. The dog 78 except for its opposite disposition is mounted in identically the same manner as the dog 77 and similar reference characters are utilized for designating like parts of each. One of the trunnions 88 of the mounting for the dog 77 has a crank 91 fixedly secured thereto, the outer end of which is provided with a pin 92 having a block 93 rotatably mounted thereon and working in a slot 94 formed in an actuating slide member 95 confined to horizontal sliding movement by guide means 96, and having an extension 97 secured by a slotted connection 98 to a bell crank lever 99 oscillated by a rod 100 to which movement is transmitted by a foot pedal 101 pivoted to the base 12 and having a bell crank extension connected by a link 106 to a bell crank 107, connected to the rod 100, the foot pedal 101 being positioned with reference to the pedal 132 so that the latter lies within convenient reach of the toe of the foot of the operator employed to manipulate the pedal 101. The trunnion 88 at the opposite end of the dog 77 is also provided with a crank 102 having a slotted connection 103 with a crank 104 secured to the trunnion 88 associated with the dog 78, whereby movement of the trunnion 88 of the dog construction 77 is transmitted in an opposite direction to the dog construction 78. The dog 77 is also provided with a lateral extension 105 and the dog 78 with a similar extension 106, disposed to lie in the path of movement of the crank members 102 and 104.

and adapted to be engaged by said crank members during one movement thereof to lift and swing the dogs pivotally about the sleeves 80 and away from the boards 24-24. Adjustment of the 5 positions of the sleeves 80 may be effected by loosening the lock nuts 86, shifting the rods 84 vertically and again securing the lock nuts 86, the vertical movement of the rods 84, through the extensions 81 rotating the sleeves 80 about the cylindrical members 87 and because of the eccentric disposition of said sleeves effecting adjustment of the operating positions of the dogs 77 and 78. Slight movement of the sleeves 80 which may take place while in relatively fixed 10 adjusted position is permitted by flexing of the rods 84.

In operation, assuming the rolls 26 and 27 to be revolving in opposite directions, and in engagement with the boards 24-24, and the dogs 20 77 and 78 retracted, the hammer head 21 will be elevated, and such elevation continued until the cam 63 thereon comes into contact with the trip member 60, moving said trip member 60 so as to press the lever 53 outwardly and oscillate the rod 25 47, movement being transmitted through the cam 49 on the rod 47 to the post 51 connected to the block 43, resulting in upward reciprocation of the block 43 and through the links 42 and the cranks 40 oscillating the eccentric bearings 30 and 31, causing recession of both of the rolls 26 and 27 30 with respect to the tail pieces 24-24, releasing engagement therewith, and permitting the hammer head 21 to drop. Just before the hammer reaches the limit of its downward movement the cam 57 of the hammer head 21 comes into contact with the slide 54, which presses the lever 52 outwardly, oscillating the rod 47 and cam 49 in an opposite direction, permitting the downward reciprocation of the block 43 and reengagement 35 of the rolls 26 and 27 with the tail pieces 24-24 and subsequent elevation of the hammer head 21, it being understood that the rolls 26 and 27 are urged to engagement through the influence of 40 gravity exerted thereon by the housing members 36, cranks 40, links 42, block 43, and post 51, the action of the cam 49 decelerating the descent of these parts and effecting gradual engagement of the rolls with the boards, thereby preserving the 45 boards against deformation and injury.

The means for regulating the stroke of the hammer are of great value, especially at the inception of the forging operation when it is desired to begin work with a series of short strokes and then gradually to increase the length of such strokes. As shown in Figure 1 the hammer 50 is in position to deliver its maximum stroke, such as required at the finish of an operation and the bracket 61 is likewise disposed substantially at its maximum elevation. Assuming however, that no more strokes are desired, the operator 55 takes his foot off the pedal 101, and the dogs 77 and 78 engage the tail piece means and hold the hammer elevated, and the finished piece of work is removed. The operator then, in preparing for 60 the next operation, and before the next piece of work is inserted into the machine, places his foot momentarily upon the pedal 101 and by expert manipulation will permit the tail piece means to slide through the dogs 77 and 78 and drop to a 65 point short of engagement with the lever 52; or if desired the hammer may be dropped through an idle stroke by disconnecting the dogs 77 and 78 by manipulation of the foot pedal 101. Meanwhile the bracket 61 has automatically returned 70 substantially to its lowermost position, and re-

mains substantially in this position until the operator desires to increase the stroke. This action occurs through the automatic operation of the means for controlling the screw. It will be noted that the clutch member 121 is normally urged by the spring 128 in a direction to engage the bevel gear 116 which rotates the screw 66 in a direction to cause lowering of the bracket 61 and this rotation continues until the bracket 61 contacts the limit stop 135 which shifts the clutch member 121 into neutral position, and stops the rotation of the screw 66, thereby maintaining the bracket 61 at its low position, so that short strokes desired at the inception of the forging operation may immediately be obtained. The foot pedal 101 may now again be depressed by the operator to release the dogs 77 and 78 and a series of short strokes delivered, the mechanism operating automatically, governed by the trip mechanism above described. When the operator desires longer strokes he uses the toe of the same foot in engagement with the pedal 101 to depress the pedal 132 and such depression causes engagement of the clutch member 121 with the gear 117, and rotation of the screw 66 in a direction to elevate 100 the bracket 61 and trip member 60, to the adjusted position desired by the operator, who will then relieve the pressure on the pedal 132 to permit the clutch member 121 to occupy a neutral position between the gears 116 and 117; if however, the operator fails to relieve the pressure and maintains the same pressure on the pedal 132 the bracket 61 will rise until it strikes the collar 134 on the rod 129, and against the pressure of the foot of the operator raise the rod 129 and throw 105 the clutch member 121 into neutral position, and when the operator takes his foot off of the pedal 132, influence of the spring 128 re-establishes engagement of the clutch member 121 with the gear 116, and causes the bracket and trip member 110 115 60 to descend to initial position.

The dogs 77 and 78 are normally urged into engagement with the boards 24-24 under the influence of gravity, and are adapted to be retracted by depression of the pedal 101, as already stated. 120 Such depression of the foot pedal 101 causes downward movement of the rod 100, clockwise movement of the bell crank lever 99, inward movement of the slide 95, clockwise movement of the crank 91, and clockwise movement of the crank 102, resulting in rotation of the cylindrical member 87 about its eccentric trunnions 88, and bodily retraction of the dog 77 horizontally away from the boards 24-24, similar movement though in an opposite direction being transmitted through the 125 crank 104 to the cylindrical member 87 of the dog 78, resulting also in bodily retraction of the dog 78 horizontally away from the boards 24-24; and preferably immediately following the inception of the bodily movement of the dogs 77 and 78 they 130 are also swung in opposite directions away from the boards 24-24 about the centers of the sleeves 80 through engagement of the cranks 102 and 104 and the extension 105 of the dog 77 and extension 106 of the dog 78, thereby lifting and swinging said dogs upwardly, this mechanism serving not only to more quickly release the boards 24-24 but also to insure that the dogs 77 and 78 are removed from the boards 24-24 a sufficient distance to prevent contact therewith during operation. The hammer may be arrested at any elevated position by releasing the foot pedal 101, bringing about a reversal of the movements of the mechanism controlling the dogs 77 and 78 140 and causing engagement of said dogs 77 and 78 145 150

with the boards 24—24 thereby preventing the hammer head 21 from continuing its descent.

Attention is called to the fact that the control mechanism may easily be adjusted to vary the length of stroke of the hammer head 21 yet operates automatically to return the bracket 61 and trip 60, from a higher adjusted position to a low position, so that short strokes may be obtained at the inception of the forging operation 10 and then gradually increased thereafter.

It should also be noted that the operating rolls are both moved toward and from engaged position, differing in this respect from all constructions of which I have knowledge and having a marked advantage in that, when released, the rolls are entirely clear of the tail pieces and free of any danger of injuring such tail pieces. In actual practice this has resulted in extending the life of the tail pieces many times as compared with ordinary constructions. Likewise the compound movement of the dogs assures rapid engagement and disengagement thereof with respect to the boards 24—24 and complete freedom of the tail boards when the dogs are in inoperative position, thereby additionally extending the life of the tail piece and providing rapid and efficient operation.

It will be understood by those skilled in the art that the embodiment herein described accomplishes at least the principal object of the invention; and it will further be understood that said embodiment is capable of uses and has advantages other than those herein particularly pointed out, and it will also be apparent that various changes and modifications may be made without departing from the spirit of the invention, and consequently the embodiment herein disclosed is illustrative only and the invention is not limited thereto.

I claim:

40. 1. A drop hammer comprising: a hammer head having a tail piece, opposed rolls engageable with said tail piece to lift said hammer head and disengageable to permit said hammer head to drop, and control means for said rolls, including an oscillatable rod confined to horizontal oscillations, a slidable trip member operable by said hammer head slidable to effect oscillation of said rod, adjustable longitudinally with reference to said rod, during operation of said hammer and a transmitting member between said trip member and said rod and disposed to effect engagement in the various adjusted positions of said trip member to thus vary the stroke of the hammer head.

55. 2. A drop hammer comprising: a hammer head having a tail piece; means for raising and dropping said hammer head; opposed dogs engageable with said tail piece for supporting the same against dropping; and means for effecting relative approach and recession of both of said dogs with respect to said tail piece, said means including a common control; means operable by said control to impart bodily movement to each of said dogs; and means operable by said control to simultaneously impart pivotal movement to each 65 of said dogs.

70. 3. A drop hammer comprising: a hammer having a tailpiece; eccentrically mounted rolls engageable and disengageable with reference to said tailpiece; gravity influenced means cooperating with said rolls, adapted to be elevated to effect relative separation of said rolls to release said tailpiece, and operable when dropped to effect engagement of said rolls with said tailpiece; control means for controlling operation of said gravity influenced means; and a swingable cam having a

contoured cam surface engageable with said gravity influenced means, the surface being contoured to gradually decelerate the drop of said gravity influenced means and effecting gradual engagement of said rolls with respect to said tailpiece. 80

4. A drop hammer comprising: a hammer head having a tailpiece; means for raising and dropping said hammer head; opposed clamps engageable with said tailpiece for supporting the same against dropping; eccentric members carrying said clamps and operable when rotated to horizontally bodily shift said clamps toward and from said tailpiece, said clamps being pivotally swingable about the axes of said eccentric members; and levers connected to said eccentric members for imparting rotation thereto in opposite directions, and means on said clamps interengageable with said levers to swing the former about their pivots. 85

5. A drop hammer machine comprising: a hammer having a tailpiece; opposed rolls mounted upon eccentric bearings, both approachable with reference to said tailpiece; and separable to release said tailpiece to permit said hammer 100 to drop; roll actuating mechanism cooperating with said rolls for effecting engagement and disengagement of both of said rolls; and control means having an adjustable element for controlling operation of said roll actuating mechanism; a rotatable screw adapted to be rotated during the rise and fall of said hammer; and a nut on said screw, operably connected with said adjustable element to effect adjustment of said element, and effect disengagement of said roll 110 actuating mechanism at different heights and thus vary the stroke of said hammer. 105

6. In a drop hammer machine, comprising: a hammer having a tailpiece; eccentrically mounted rolls engageable and disengageable with respect to said tailpiece; mechanism connected to both of said rolls and movable to effect simultaneous approach or recession of both of said rolls with reference to each other; gravity influenced means connected with said mechanism 115 and operable therethrough normally to urge both of said rolls toward engagement with said tailpiece; and control means cooperable with said mechanism, operable by movement of said hammer, for elevating and permitting descent of said 120 gravity influenced means to thereby operate said rolls; said control means comprising means operable to retard the descent of said gravity influenced means to effect gradual engagement of said rolls. 125

7. A drop hammer comprising: a hammer head having a tailpiece; means for raising and dropping said hammer head; opposed clamps engageable with said tailpiece for supporting the same against descent, each of said clamps being rotatably mounted upon an eccentric bearing and each bearing having a crank, said cranks being interconnected whereby operation of one effects movement of the other to rotate said eccentric bearings and effect shifting movement of said 140 clamps toward and from each other; each of said clamps having means projecting into the path of movement of said cranks, whereby movement of said cranks rotates said clamps as well as shifts the same. 135

8. A drop hammer machine, comprising: a hammer having a tailpiece; eccentrically mounted rolls engageable and disengageable with reference to said tailpiece; mechanism connected to said rolls and movable to effect simultaneous ap- 145

- proach or recession of both of said rolls with respect to each other; gravity influence means connected with said mechanism and operable through said mechanism normally to urge both of said 5 rolls in one direction with reference to said tailpiece; an elongated oscillatable rod oscillatable about its longitudinal axis and disposed along the path of said hammer and having means adapted to be moved by said hammer to oscillate said oscillatable rod; and means for transmitting oscillatory movements of said rod to said mechanism whereby movement in one direction effects elevation of said gravity influenced means, and movement in a reverse direction permits descent of said gravity influenced means. 15
9. A drop hammer machine, comprising: a hammer having a tailpiece; operating rolls engageable and disengageable with respect to said tailpiece; mechanism connected with both of 20 said rolls and operable to effect simultaneous approach or recession of both of said rolls with respect to each other; an elongated oscillatable rod oscillatable about its longitudinal axis and disposed along the path of said hammer and having means adapted to be moved by said hammer unit to oscillate said oscillatable rod; and means for transmitting oscillatory movements of said rod to said mechanism whereby movement in one direction effects movement of said rolls to elevate said hammer, and movement in a reverse direction effects movement of said rolls to permit descent of said hammer. 25
10. A drop hammer machine comprising: a hammer having a tailpiece; actuating means engageable with respect to said tailpiece to lift said hammer and disengageable with respect to said tailpiece to drop said hammer; and mechanism for effecting engagement and disengagement of said actuating means, including control means initially disposed in predetermined position, adjustable along the path of the hammer, and adapted to be operated by said hammer in its adjusted position to effect disengagement of said actuating means to thus vary the stroke 40 of said hammer, and a screw operatively connected with said control means and under the control of the operator, and rotatable in reverse directions to so adjust said control means; and automatically operable clutch means for rotating said screw to return said control means to said predetermined position following adjustment thereof. 50
11. A drop hammer machine comprising: a hammer having a tailpiece; actuating means engageable with respect to said tailpiece to lift said hammer and disengageable with respect to said tailpiece to drop said hammer; and mechanism for effecting engagement and disengagement of said actuating means, including control means initially disposed in predetermined position adjustable along the path of the hammer, and adapted to be operated by said hammer in its adjusted position to effect disengagement of said actuating means to thus vary the stroke of 55 said hammer, and power means operatively connected with said control means, and under the control of the operator, and operable to so adjust said control means; and automatically operable means for actuating said power means to return said control means to said predetermined position following adjustment thereof. 65
12. A drop hammer machine comprising: a hammer having a tailpiece; actuating means engageable with respect to said tailpiece to lift said hammer and disengageable with respect to said 75
- tailpiece to drop said hammer; an oscillatable rod disposed along the path of said hammer and having trip means adapted to be moved by said hammer to oscillate said oscillatable rod, said trip means being initially disposed in predetermined position and adjustable along the path of said rod; means for transmitting movements of said rod to said actuating means; power means operatively connected with said trip means, and under control of the operator, and operable to adjust said trip means; and automatically operable means for actuating said power means to return said trip means to said predetermined position following adjustment thereof. 80
13. In a drop hammer machine, comprising: a hammer having a tailpiece; operating rolls adapted to be engaged and disengaged with respect to said tailpiece, and each mounted upon an eccentric bearing; a crank connected to each of said eccentric bearings, and each crank having one end of a link pivotally connected thereto; gravity influenced means connected with the opposite ends of said links, and operable through said links and cranks normally to urge both of said rolls simultaneously toward engagement 100 with said tailpiece; an elongated oscillatable rod oscillatable about its longitudinal axis and disposed along the path of said hammer and having means adapted to be moved by said hammer to oscillate said oscillatable rod; and means for transmitting oscillatory movements of said rod to said mechanism whereby movement in one direction effects elevation of said gravity influenced means, and movement in a reverse direction permits descent of said gravity influenced means. 105
14. In a drop hammer machine, comprising: a hammer having a tailpiece; operating rolls adapted to be engaged and disengaged with respect to said tailpiece, and each mounted upon an eccentric bearing; a crank connected to each of said eccentric bearings, and each crank having one end of a link pivotally connected thereto; gravity influenced means connected with the opposite ends of said links, and operable through said links and cranks normally to urge both of said 115 rolls toward engagement with said tailpiece; control means for elevating and permitting descent of said gravity influenced means to thereby operate said rolls; opposed clamps engageable with said tailpiece for supporting the same 120 against descent, each of said clamps being rotatably mounted upon an eccentric bearing and each bearing having a crank, said cranks being interconnected whereby operation of one effects movement of the other to rotate said eccentric 125 bearings and effect shifting movement of said clamps toward and from each other; each of said clamps having means projecting into the path of movement of said cranks, to be moved thereby to rotate said clamps as the same are shifted. 130
15. A drop hammer machine comprising: a hammer unit, including a hammer; actuating means for elevating said hammer unit; an oscillatable rod disposed along the path of said hammer and having a lateral extension extending 140 longitudinally along said rod; means for transmitting oscillatory movements of said rod to said actuating means; a member mounted for adjustment along the path of said hammer; and means movably carried by said member, adapted to engage the lateral extension of said oscillatable rod at various positions therealong, and disposed to be actuated by movement of said hammer. 145
